WIRE HANDLING TOOL

Filed Oct. 26, 1925

FIG. 1.

FIG. 2.

FIG. 3.

INVENTOR
James A. Lindsay
BY
Charles S. Evans
his ATTORNEY

UNITED STATES PATENT OFFICE.

JAMES A. LINDSAY, OF OAKLAND, CALIFORNIA.

WIRE-HANDLING TOOL.

Application filed October 26, 1925. Serial No. 64,734.

My invention relates to tools for handling wire and especially to a tool of particular usefulness to workers on concrete forms.

One of the objects of the invention is the provision of a tool for securing the tie-wires in concrete forms with a minimum expenditure of time and energy.

Another object of the invention is the provision of a tool embodying those instrumentalities which a workman needs in applying or removing the tie-wires in a concrete form.

Another object of the invention is the provision of a tool for tightening and tying the tie-wires embodying means for clamping the tool in place on the wires during momentary absence of the workman.

The invention possesses other objects and features of advantage some of which, with the foregoing, will be set forth in the following description of the preferred form of my invention which is illustrated in the drawings accompanying and forming part of the specification. It is understood that I do not limit myself to the showing made by the said drawings and description, as I may adopt variations of the preferred form within the scope of my invention as set forth in the claims.

30 Referring to the drawings:

Figure 1 is a side elevation of my wire-handling tool.

Figure 2 is an end elevation of the tool.

Figure 3 is a plan view of the tool, showing the same applied in the first step of tightening and twisting the wires for reenforcing a concrete form.

In broad terms my invention comprises a tool having opposed jaws, and handles for operating the jaws, with a fulcrum arranged adjacent the jaws so that by placing the fulcrum against a convenient supporting surface, a very large stress may be applied to the object held in the jaws. Means are provided for clamping or locking the jaws upon the object held therebetween, and cutting means are also provided adjacent the jaws.

In terms of greater detail the tool of my invention comprises the arms 6 and 7, each terminating in a head 8. The arms are crossed and pivotally connected by the pivot pin 9. In each head a tapered groove is arranged in which is seated a complementary portion 11 of the jaw 12, which, as shown in Figure 2, extends a considerable distance on

each side of the head 8. The adjacent faces of the jaws are roughened to provide a better gripping surface.

The taper of the groove in which the jaws seat, is in the same direction in both heads, so that the jaws are always in line, and are not misaligned by tapping them to tighten them in their seat if that be necessary. Integrally formed on each of the jaws 12, is a cutting jaw 13, and these jaws are arranged in a plane perpendicular to the pivotal axis of the pivot pin 9.

Preferably integrally formed with the arm 7 is a leg 14, which projects downwardly and ends below the jaws. The leg provides a fulcrum about which the tool as a whole may be moved.

Pivots connected on the end of the arm 6 opposite the head of the tool is a latch 16, adapted to engage the arcuate seat 17, oppositely disposed on the arm 7. The arcuate seat is formed on an increasing radius about the axis of the pivotal mounting of the latch, and is provided with notches 18 in which the latch optionally may be caught. Since the tool is primarily intended for handling wire, this latch arrangement adapts the tool to be clamped upon wire of different gauges.

In setting up forms for pouring concrete, it is common practice to retain the boards or planking 21 against the spacing members 22, by vertical studs or members 23, oppositely disposed on the outside of the planking. Wire loops 24 are then passed about the stud and the free ends 26 twisted to retain the planking against the outward thrust of the concrete 27. The wire handling tool of my invention is particularly adapted for grasping the free ends of the wire as shown in plan in Figure 3. With the leg 14 positioned against the near stud, downward pressure on the handles 6 and 7 pulls the wire tight against the opposite stud, and with the twisting of the ends 26 together, the wire is tightened about the studs and holds them securely in place.

Because of the wide jaws, the wire ends 26 may be readily grasped without a preliminary twisting together, and the fulcrum leg permits the proper tension to be applied to the wire during the operation, so that only a turn or two to secure the wire is necessary. Heretofore more or less twisting of the wire has been necessary to place it under the proper tension. With my tool, the wire may

be pulled taut, after which one or two turns is sufficient. A very large saving in time is thus effected, and a better piece of work done. Occasionally it is desirable for the workman 5 to leave a particular wire loop and go to the opposite side of the form, or to the adjacent loop. The latch for clamping the tool upon the wire is then very convenient, as it permits the tool to be left hanging on the wire, 10 and ready for continued use. By the use of this tool, a workman is enabled to pass rapidly along, twisting and tightening the tie wires with a minimum of time and effort.

In taking down the forms after the concrete has set, my wire-handling tool will also 15 be found exceedingly valuable. Where it is necessary to pull a wire free, the fulcrum leg is useful, and because of the peculiar position of the cutting jaws, the wire loops may be cut 20 with the cutting tool in a convenient and easy position.

I claim:

1. A tool comprising pivotally connected levers embodying opposed gripping jaws at 25 one side of the pivot, and means constituting a fulcrum for said tool rigid with one of said levers and attached thereto at a position on the opposite side of the pivot, said fulcrum means extending on each side of the plane 30 which perpendicularly bisects the pivotal connection.

2. A tool comprising pivotally connected

levers embodying opposed gripping jaws at one side of the pivot, and a fulcrum leg attached to one of said levers at a position on 35 the opposite side of the pivot, said leg having a bearing edge parallel to the pivotal axis and extending past the pivotal connection on each side of the plane which perpendicularly bisects the pivotal connection to give lateral 40 stability to the tool.

3. A wire handling tool comprising pivotally connected levers embodying opposed gripping jaws at one side of the pivot, and a fulcrum leg on one of said levers attached 45 thereto at a position on the opposite side of the pivot, the gripping edges of said jaws and the bearing edge of said fulcrum leg being parallel to the pivotal axis of the levers and extending laterally past the pivotal connection 50 on each side of the plane which perpendicularly bisects the pivotal connection.

4. In a tool, a pair of levers comprising handle portions and jaw portions, a pivotal connection for said levers positioned between 55 said handle and jaw portions, and a fulcrum leg rigid and co-planar with one of said levers and connected to the handle portion thereof at one side of the pivotal connection, and extending obliquely past said pivotal 60 connection toward the jaws.

In testimony whereof, I have hereunto set my hand.

JAMES A. LINDSAY.
